IGNITION TIMER

James L. Arthur and William Thompson, Anderson, Ind., assignors to General Motors Corporation, Detroit, Mich., a corporation of Delaware

Application November 9, 1935, Serial No. 48,998

15 Claims. (Cl. 200—19)

This invention relates to ignition timer distributors used in conjunction with automotive engines, and is particularly directed to the type of suction controlled timers.

5 One object of this invention is to provide a ball bearing support for the breaker plate of an ignition distributor, in which one of the ball races is provided by an integral part of the breaker plate, and the balls are spring urged into 10 position by a yieldable section of the breaker plate.

Another object of the invention is to provide a 15 breaker plate and a ball bearing race member of integral construction and having a yieldable section providing spring loading means for the balls when the assembly is mounted in a distributor.

A further object of the invention is to provide an ignition distributor in which the breaker plate is directly supported from the wall of the cup by 20 ball bearings whose races are provided by the cup and an integral part of the breaker plate.

A further object of the invention is to improve suction controlled timers by providing a stop post on a bracket mounting the suction unit upon 25 the cup, which stop limits the movement of a link making a direct connection between the suction unit and breaker plate.

A further object of the invention is to provide 30 a ball bearing support for a breaker plate in an ignition distributor, wherein the ball bearings are disposed in a plane passing through the contact points and rubbing block engagement with the cam, whereby the moment of force tending to tilt the breaker plate is substantially eliminated.

35 Further objects and advantages of the present invention will be apparent from the following description, reference being had to the accompanying drawings wherein a preferred embodiment of one form of the present invention is clearly shown.

In the drawings:

Fig. 1 is a vertical sectional view of a timer distributor incorporating the improvements, being a view substantially as indicated by the line and arrows 1—1 of Fig. 2.

Fig. 2 is a top plan view of the interior of the timer mechanism with parts broken away to show the suction unit in section, the view being substantially that illustrated by the line and arrows 2—2 of Fig. 1, or with the distributor cap and rotor removed.

Fig. 3 is a perspective view of the improved breaker plate showing parts of the ball bearing assembly in section.

Figs. 4 and 5 are sectional and detail views respectively of a fragment of the ball retainer.

Fig. 6 is a fragmentary view in section illustrating certain modifications of the breaker plate and a means by which the ball bearing support is 5 perfected.

Fig. 7 is a view partly in elevation and partly in section substantially as indicated by the line and arrows 1—1 of Fig. 2.

Fig. 8 is a view in elevation with parts shown in 10 section substantially as indicated by the line and arrows 8—8 of Fig. 7.

Fig. 9 is a fragmentary view similar to Fig. 2, but showing the breaker plate and movable elements of the suction unit in an adjusted position. 15

Fig. 10 is a perspective view of the suction unit and breaker plate connecting link.

Fig. 11 is a fragmentary view in cross section substantially as indicated by the line and arrows 11—11 of Fig. 2, and illustrating the means for anchoring the ball spacer. 20

In ignition distributors of the prior art where a shiftable breaker plate is actuated by a suction unit, the devices invariably offer considerable 25 resistance to movement and therefore render the suction control means but partly efficient. Some constructions have been proposed for mounting the breaker plate by means of ball bearings, but in main, these prior art devices in order to reduce the frictional resistance are either so flexible or so loosely assembled, that the support of the circuit breaker by means of the breaker plate is rather unstable, and the high frequency operation of the circuit breaker in opening the contacts through the successive engagement of the cam and rubbing block, causes the breaker plate to chatter or rattle upon its ball bearing support, and in some instances to wobble or oscillate laterally which latter gives rise to considerable 30 variation in contact opening and wear of the moving parts. 35

The invention disclosed herein overcomes these objections, and provides a construction characterized by minimum frictional resistance, though 45 assembled with sufficient rigidity to eliminate the looseness or rattling and wear of the parts. These improvements are accomplished by preparing the inner surface of the distributor cup to form an outer race way, and by fashioning the breaker 50 plate in the form of a shallow cup whose side walls are spun or otherwise formed into an inner race way, so that a series of ball bearings retained in spaced relation by a ball retainer may be disposed in the ball races. The balls may be 55

assembled in the inner race before the plate is positioned in the cup; and thence by means of vertical grooves extending from the edge of the distributor cup to the outer race way, the assembled breaker plate and ball bearing parts may be passed to position within the cup and so that the balls rest in the outer race. The breaker plate is provided with an arcuate slot extending through the side wall and into the bottom wall thereof so as to provide a yieldable section disposed behind one or more of the balls when assembled within the cup. This yieldable section provides integral means for springing the balls into their respective seats in the races.

15 A more detailed explanation of the invention is to be found in the following parts of the specification, wherein it illustrates a housing of cylindrical form for a timer-distributor fashioned to provide a bottom wall 12, with oppositely extending bosses 14 and 16 forming a journal bearing for a distributor shaft 18. The shaft 18 has a reduced extension 20 upon which there is rotatably supported a cam 22, and centrifugally connected to be driven by the shaft 18 through speed responsive mechanism 24. Fitted within the bottom of the housing 10, there is a partition member 26 that fits about the boss 14 and is spaced from the bottom wall 12 of the cup to provide a lubricant chamber 28, that has communication with the bearing for the shaft 18 through the cross bores 30, a fixture 32 being provided for the addition of lubricant as it is needed. Mounted on the upper end of the cam 22 there is a rotor 34 having conductive elements 36 and 38 adapted to function with terminal members 40 and 42 respectively supported by a distributor cap 44 closing off the open end of the housing 10.

The inner surface of the cylindrical wall is provided with a peripheral groove 50 spaced somewhat from the terminal edge 52 of the housing. Vertical grooves 54 lead in from the edge of the cup and open into the annular groove 50. These formations provide an outer race way for a series of balls 56 that operate to support a breaker plate 58. The breaker plate is in the form of a shallow cup having a flange 60, which flange is formed into a groove section substantially as indicated at 62, that provides an inner ball race for the ball bearings 56. The breaker plate is of that over-all dimension that it will firmly engage a plurality of the balls 56 when the plate is assembled within the housing wall. This assembly of the plate within the housing is accomplished by inserting the balls in the race ways 62 of the plate flange when the same is positioned at the edge 52 of the housing, the balls being disposed coincident with the vertical grooves 54, and a ball retainer ring 64 having ball receiving apertures 66 being positioned between the flange of the breaker plate and the housing. These ball receiving apertures 66 are equally spaced and coincident with the vertical grooves 54 so that when the retainer is assembled with the housing and breaker plate, the retainer 64 maintains the balls substantially equally spaced within their races. The ball retainer 64 may be made up of a strip of sheet metal having its ends 68 and 70 spliced or united in some way such as illustrated in Figs. 4 and 5 of the drawings. With the breaker plate, balls and ball spacing band adjusted in this position at the mouth of the cup 10, the assembly may thence be moved into operating positions as illustrated in Fig. 1, in which the balls 56 have been moved to their position in the outer race. Rotating the assembly within the housing will then assume the position illustrated in Fig. 2 where it will be noted that the ball bearings have been angularly displaced to such an extent that they will be out of registry with the vertical ways 54 and thereby prevented from being laterally displaced. A stop pin 72 passing through both the housing wall 10 and the band 64 will prevent the balls from being displaced.

The breaker plate 58 has special provisions for 10 springing the balls, or for maintaining them in firm engagement with each of the race members. In the present instance three of the ball bearings 56 are used as a support for the breaker plate and the springing of the balls is accomplished 15 by punching or cutting a slot 74 in the bottom wall of the breaker plate one end of which is opened through the flange 60 of the breaker plate by means of a saw cut or slit 76, thus providing a yieldable section 78 of the breaker plate flange 20 that engages behind one of the balls 56 set near the free end of the yieldable section and having a hinge portion near an adjacent ball 56. Due to the formation of the ball race in the flange of the plate, there is then sufficient inherent resilience in the body of the plate, and especially if the same is made slightly oversize as in the instance of piston rings, to maintain all of the balls in firm engagement with their race ways, and to provide adequate and rigid support for 25 the breaker plate assembly. The yieldable section pressing against the ball 56 and being under a stress of compression, forces the opposite side of the breaker plate assembly and incidentally the other two balls 56 into firm engagement with 30 the race way 50 at the respective points.

In the modification shown in Fig. 6, the housing wall 16 is formed to provide a ledge 11, adapted to receive a ring 13 having their adjacent covers machined to cooperate in forming an outer 40 race way 51. Spaced from the ledge 11 and intermediate the ledge and the rim 52 of the cup there is an annular shouldered groove 55, adapted to receive the end of a spring member 17 formed to engage and urge the ring 13 toward the ledge 45 11, and thus add to the springing of the ball in their races.

Here too, there is illustrated some modifications of the breaker plate. It is of inverted cup form as is illustrated at 59 in Fig. 6, the flange 51 having the formed race way 63 adapted to receive the balls 55 when seated in the race way 51. The ball retainer ring 64 acts in the same capacity as in the form first described. Since the flange of the breaker plate here is downward, the circuit breaker mechanism is mounted outside of and above the bottom of the plate so as to cooperate with the cam 22. If desired the body of the plate may also be provided with the yieldable section like that afore described, but the spring 17 crowding the ring 13 against the balls, has been found sufficient to spring load the balls.

There is secured in the breaker plate 58 a pivot post 80 about which there oscillates the contact bracket 82 adjustably held against the plate 58 by a clamp screw 84, there being provided a slot 86 and eccentric device 88 for moving the bracket to adjust the amount of contact opening. The bracket 82 also provides an extension 90 supporting a fixed contact 92, as well as an apertured lug 94. Surrounding the pivot post 80, and disposed above the end of the bracket 82 there is a dielectric bushing 96 supporting a contact arm 98 provided with a movable contact 100 for sepa-

5 rable engagement with the fixed contact 82. A rubbing block 102 is also carried by the contact arm 88 and is adapted to be actuated by the cam 22 upon rotation thereof, a conducting spring 104 being anchored to the arm 88 and secured to the lug 84, for urging the arm toward the cam and for making electrical connection with a terminal screw 106 secured to the lug 84, and to which a lead 108 communicates with a condenser 110 grounded to the breaker plate 58 by means of a clip 112 and screw 114. A second lead 116 joins the terminal screw 106 with a terminal post 118 insulatingly supported in the side wall of the cup 10.

15 Referring to Fig. 7, it will be noted that the aligned axes of the contacts 82 and 108 and now particularly, the central point of engagement between the cam 22 and the rubbing block 102 are substantially coincident with a plane passing through the axes of the ball bearings. By 20 the term "central point of engagement" is meant a point midway along the line of contact between the rubbing block 102 and the cam 22. In other words, if one were to consider the force applied 25 by the cam 22 to the rubbing block as being concentrated at one point, that point would be the "central point of engagement" between the cam and rubbing block. It is desirable to so locate the circuit breaker and cam with respect to the 30 ball bearings that this "central point of engagement" between the cam and rubbing block is substantially in the plane of the ball bearings, because the force exerted by the cam upon the rubbing block then has substantially a zero movement of force with respect to the plane of the 35 ball bearings. In other words, the cam exerts forces upon the rubbing block such that, if these forces were concentrated at one point, the resultant force would be applied in the plane of 40 the ball bearings. Hence the actuation of the circuit breaker mechanism will not then tend to tilt or wobble the breaker plate and thus interfere with rotation by the suction operated plate adjusting means. Moreover the present construction eliminates such wobbling of the plate as 45 would upset the correct timing of the ignition.

The speed responsive mechanism 24 includes a weight plate 120 press fitted upon a portion of the shaft 18 as at 122, and provides a pair of diametrically disposed pivot posts 124 whose ends 50 are secured within the base 120 and oscillatably support a pair of flyweights 126, having arms engaging a cam bar 128 secured on the lower end of the cam 22, as indicated at 130. Mounted in opposite ends of the cam bar 128 there are spring posts 132, to the ends of which are secured springs 134 tending to keep the flyweights 126 in the in-position. A holdown plate 136 is secured to the weight base 120 and spaced above the flyweights 55 and cam bar, but tending to keep them in properly assembled relation. The holdown plate 136 has an overhanging flange 138, having deformed portions for stops limiting the outward throw of the flyweights. Inasmuch as this speed responsive mechanism is the subject matter of another 60 application, further description is not deemed necessary at this time. It is to be considered that rotation of the shaft 18 will act through the speed responsive mechanism to drive the cam 22 which effects the operation of the circuit 65 breaker mechanism. As the speed of rotation of the shaft 18 increases the flyweights responding to the increased speed move out by centrifugal force and in so doing tend to rotate the cam 22 upon the extension 26, all in accordance with the 70

75 engine speed, thereby altering the time of interrupter operation relative to shaft rotation.

Means are provided for actuating the breaker plate 58, or 58, and for defining the limits of that actuation, whereby further variation or alteration in the time of circuit breaker operation may be accomplished. The particular means provided here embrace a fluid displacement or suction unit 150 comprising a pair of cups whose flanged rims are spun over one another and compressed about the periphery of a flexible diaphragm 156, the cup 154 being rigidly secured to a flat portion 158 of a press metal bracket 160 that is mounted upon the outer periphery of the housing cup 10 by means of the screws 162. The 10 bottom of the cup 154 and the flat portion 158 of the bracket are apertured at 164 substantially as illustrated in Fig. 8, such as to provide the parallel branches of the opening 166 separated by a tongue 168, and the cylindrical wall of the 20 housing 10 is cut away at 160 so as to make provision for passage and movement of a link 182 joining the diaphragm 156 with the breaker plate 58.

The link 182 has an aperture 184 for receiving 25 a pin 186 forming a pivot for the link and secured to the breaker plate by means of riveting as at 188. The other end of the link is provided with an opening 190 that is disposed to loosely fit over the tongue 168 of the bracket 160, while the 30 body of the link 182 extends through the slot or aperture 180 and is connected to the breaker plate 58. Fixed to the bifurcated end of the link 182 such as to close off the aperture 190 there is a washer or plate 192 whose aperture 194 makes provision for receiving a stud 196 extending from a 35 spring receiving cup 198 and extending through the diaphragm 156 and washer 192 where it is riveted over, thus providing a driving connection between the diaphragm 156 and breaker plate 58. 40 Received within the spring cup 198 is a spring 200 engaging the bottom of a nipple 202 by which fluid connection of the chamber is made with the induction pipe of the engine.

As thus constructed, a unit is provided adaptable to shift the breaker plate in response to variations in engine suction conditions, in that manifestation within the chamber 150 sufficient to compress the spring 200 will rotate the breaker plate 58 within the housing 10 upon the ball bearing from that position illustrated in Fig. 2 where the end of the stud 196 is against the stop tongue 168, to that position illustrated in Fig. 9 where the breaker plate 58 has been rotated in a clockwise direction and the opposite end of the aperture 190 55 is engaged by the tongue 168. The amount of movement of the breaker plate can be regulated by either lengthening or shortening the aperture 190 to meet the desired conditions, but in Fig. 9, the relative perfected adjustment of the plate is 60 illustrated by the dotted line showing of the contact supporting bracket 82, for the original position, while the full line position is illustrative of the shifted breaker position. The shifting movement of the breaker plate is accomplished with a 65 minimum amount of friction due to the ball bearing support on the large diameter ball races, provided by the housing wall and flange of the breaker plate. The point of engagement between the separable contacts 82 and 100 and the central 70 point of engagement between the cam 22 and rubbing block 102 being substantially coincident with a plane passing through the axes of the ball bearings, actuation of the circuit breaker mechanism will not then tend to tilt or wobble the 75

breaker plate, since the force exerted by the cam upon the rubbing block has a substantially negligible moment of force with respect to the plane of circuit breaker support.

5. While the embodiment of the present invention as herein disclosed, constitutes a preferred form, it is to be understood that other forms might be adopted, all coming within the scope of the claims which follow.

10. What is claimed is as follows:

1. In a timer having a housing including a bottom wall and a cup like cylindrical wall, a cam and driving shaft journaled for rotation in the bottom wall, the combination with said housing

15 of a breaker plate having an upstanding flange, ball bearings supporting the flange of the breaker plate from the cylindrical wall of the cup, a circuit breaker mounted upon the breaker plate and having a rubbing block engaged by said cam and

20 so located with respect to the bearings that the central point of engagement between the cam and rubbing block is substantially coincident with the plane of the bearings, and means for rotating the breaker plate.

25 2. The combination set forth in claim 1 further characterized by having the breaker plate notched in from its periphery so as to render its flange flexible at one portion, said flexible flange portion engaging at least one of the balls of the ball bearing for the purpose specified.

3. In a timer having a housing including a bottom wall and a cup like cylindrical wall, a cam and driving shaft journaled for rotation in the bottom wall and a circuit breaker to be operated 35 by the cam, the combination comprising a flanged breaker plate supporting the circuit breaker, said cylindrical wall and breaker plate flange both being formed to provide ball races, a plurality of ball bearings disposed within the races for mov- 40 ably supporting the breaker plate from the housing wall, and a ball spacer interposed between the breaker plate flange and the cylindrical wall for substantially equally distributing the ball bearings.

45 4. The combination set forth in claim 3, wherein means are provided projecting through the timer housing for limiting rotative movement of the ball spacer through a restricted range.

50 5. The combination set forth in claim 3, wherein in said ball spacer comprises a ring like member of thin stock surrounding the breaker plate and spaced therefrom, and apertured for reception of the balls in spaced relation.

55 6. The combination set forth in claim 3, wherein in the plane of the ball bearings is substantially coincident with the central point of engagement between the cam and rubbing block whereby cam operation of the circuit breaker will not tilt or wobble the breaker plate.

60 7. In a ball bearing distributor timer having a cylindrical housing wall internally grooved to provide a race way, and a cam mounted on a shaft for rotation within the housing, the combination comprising, a cup like breaker plate whose cylindrical wall provides an inner race way, a series of ball bearings disposed in both race ways for supporting the breaker plate from the housing wall, a circuit breaker mounted on the breaker plate and operated by said cam, the

65 central point of engagement between the cam and rubbing block being substantially coincident with a plane passing through the centers of said ball bearings, and means for rotating the breaker plate relative to the housing and cam.

75 8. The combination set forth in claim 7, where-

in the inner ball race comprises a groove spun into the cylindrical wall of the breaker plate.

9. In a ball bearing distributor timer having a cylindrical housing wall internally grooved to provide a race-way, a cam mounted on a shaft for rotation within the housing, the combination comprising a cup like breaker plate whose cylindrical wall provides an inner race way, a series of ball bearings disposed in both race ways for supporting the breaker plate from the housing wall, a circuit breaker mounted on the breaker plate and operated by said cam, the central point of engagement between the cam and rubbing block being substantially coincident with a plane passing through the center of said ball bearings, means for rotating the breaker plate relative to the housing and cam, and means comprising a part of the cup-like breaker plate for spring urging all of the ball bearings into seating engagement with both race ways.

10. The combination set forth in claim 9, wherein the bottom wall of the cup-like breaker plate is provided with an arc-like slot, which slot opens through the periphery of the plate to provide a yieldable section of the breaker plate, said ball bearings being disposed within the race ways such that one ball is yieldably engaged by the yieldable section of the breaker plate.

11. In an ignition timer having a housing providing a cylindrical wall, the combination of a breaker plate having an integral cylindrical flange, said flange forming a complete inner race for a ball bearing, means including the cylindrical wall of the housing providing a part at least of an outer ball race, a series of ball bearings disposed in both races and supporting the breaker plate from the cylindrical housing wall, and means spring urging the balls into firm engagement with both races whereby rotation of the breaker plate may be accomplished relative to the housing without any attendant lateral motion of the breaker plate.

12. In a suction controlled timer including a housing having a bottom wall and a cup like cylindrical wall, the combination of a cam and driving shaft journaled for rotation in the bottom wall, a circuit breaker to be operated by the cam, a flanged breaker plate supporting the circuit breaker, said cylindrical wall and breaker plate flange both being formed to provide ball races, a plurality of ball bearings disposed within the races for movably supporting the breaker plate from the housing wall, and means including an integral part fabricated from the breaker plate itself providing spring loading means for the balls.

13. In an ignition timer having a friction reducing bearing for supporting a breaker plate and including an outer race and an inner race with interposed balls, the combination of one race member with a breaker plate, a circuit breaker including a rubbing block and carried by the breaker plate, and a cam for engaging the rubbing block said breaker plate being so located with respect to its race member that the plane of the balls is substantially coincident with the central point of engagement of the cam and rubbing block.

14. In an ignition timer having a friction reducing bearing for supporting a breaker plate and including an outer race and an inner race with interposed balls, the combination with one of the races of a one-piece breaker plate and race member, a circuit breaker including a rubbing block and carried by the breaker plate and a

cam for engaging the rubbing block said breaker plate being so located with respect to its race member that the plane of the balls is substantially coincident with the central point of engagement of the cam and rubbing block, and means incorporating a part of the breaker plate for spring loading a ball in the races.

5 15. In an ignition timer having a housing pro-

viding a ball race means, the combination with the race of a circuit breaker assembly comprising a one-piece breaker plate and ball race member, and means incorporating a part of the breaker plate for spring loading a ball in the races.
